CLAIM

The ornamental design for a toilet, as shown and described.

DESCRIPTION

FIG. 1 is a perspective view taken from the top, front and left side of a toilet showing our new design;

FIG. 2 is a top plan view thereof;

FIG. 3 is a left side elevational view thereof;

FIG. 4 is a right side elevational view thereof;

FIG. 5 is a front elevational view thereof; and

FIG. 6 is a rear elevational view thereof.

The broken line representation of an access panel in FIG. 4 is for the purpose of illustration only.
